UNITED STATES PATENT OFFICE

EMIL A. MEYER, OF SPRINGFIELD, OHIO

ILLUMINATED CLOCK

Application filed May 24, 1928. Serial No. 280,185.

The present invention relates to illuminated clocks and more particularly to an electrically illuminated alarm clock.

The principal object of my invention is to provide a clock which includes a means to illuminate the dial when the alarm is sounded, thus lighting the bed-room and aiding response to the alarm.

Another object of the invention is to provide means on a clock whereby the clock may be illuminated whenever desired.

A still further object of the invention is to so construct the device that the alarm gong and the light may be cut off by separate operating means, thus permitting the use of the light bulb as a source of illumination after the alarm gong has been shut off.

Another object of my invention is to so construct the circuit making and breaking means used in my invention that they may safely be used on either a house current or a battery.

A still further object of the invention is to provide a device having the characteristics set forth above which will be readily and economically manufactured and which will have a minimum of operating parts.

In the drawings, wherein like numerals refer to similar parts throughout the several views,

Figure 1 is a front elevation of my illuminated clock.

Figure 2 is a rear elevation of the clock, with the casing partly broken away, and

Figure 3 is a fragmental rear elevation, partly in section, showing the operating parts comprising my circuit operating means.

The numeral 5 designates the casing of my clock, which casing includes a front wall 6, side walls 7, and a top and a base indicated by the numerals 9 and 10, respectively. The rear wall 11 is provided with a door 12 to permit access to the casing and the operating parts therein. A clock dial 13 is carried on the front wall 6, and a light bulb 14 is mounted above the dial, as shown. The clock dial includes an alarm-setting dial 15, such as is common to alarm clocks.

Within the casing 5 there is mounted a clockwork mechanism 16, preferably of the

usual type and including an alarm spring or alarm driving shaft 17 provided with a winding handle 18. A pinion 19 on the alarm spring shaft 17 meshes with a pinion on alarm striker gear shaft 20 to drive the latter and the striker gear 21 fixed thereto. The striker 22 is mounted on a shaft 23 and the latter shaft carries lugs or cams 24 adapted to be engaged by the teeth of the striker gear 21 to vibrate the alarm striker, all in the customary manner. The remaining parts of the clockwork mechanism are well-known and are shown diagrammatically.

I provide an actuating pin 25 which is fixed on the alarm spring shaft 17 and which radially projects therefrom to engage a squared trip pin 26 vertically and slidably mounted in an angle bracket 27 fixed upon one side of the frame of the clockwork mechanism 16. The slideable trip pin 26 includes a flat leaf spring 28 at its upper end. This spring permits the actuating pin to pass pin 26 on winding movement of alarm shaft 17, since the spring will bend to accommodate this movement. A stop pin 29 projecting at right angles from the slideable pin 26 limits the upward movement of slideable pin 26. Since squared pin 26 cannot rotate in bracket 27, the flat side of spring 28 will always be presented to actuating pin 25.

A switch panel 35 of insulating material is fixed within the casing 5 on the rear side of the front wall 6 and beneath the clockwork mechanism 16. A bell crank 36 is pivotally mounted on the panel 35 in such a position that one arm 37 will be horizontally disposed and a laterally projecting lug 38 thereon will contact with the lower end of slideable pin 26. A coil spring 39 about the axis of the bell crank 36 holds the arm 37 and lug 38 up against the lower end of pin 26 and the pin 26 is thus held up so that its upper end (flat spring 28) will be in the path of the actuating pin 25. The other arm 40 of the bell crank 36 also carries a rearwardly projecting lug 41 at its free end and the movement of the bell crank due to the action of spring 39 is limited by a stop 42 mounted on panel 35 in the path of lug 41.

A switch blade 60 is pivotally mounted at

43 on the panel 35 and is adapted to close the light circuit by contacting with fixed contact members 44. An arm 45 is fixed to the axis of blade 60 and extends in a direction substantially diametrically opposite to the blade and toward bell crank 36. A spring 46 tends to draw arm 45 upward and thus move switch blade 60 downwardly to contact with fixed contact 44, but arm 45 is normally held down by the lug 41 on bell crank arm 40, thus keeping the switch in open position. The stop 42 does not project sufficiently far forward to be in the path of arm 45.

My device may be connected either to batteries or to a house lighting circuit, the current being supplied by wires led into the casing 5 through an insulating collar in one side wall. One side of the circuit is connected to contact blade 60. Light bulb 14 is in a line 47 connecting the other side of the light circuit to fixed contact 44.

The operation of my device is as follows:— The alarm may be set in the usual manner, and when the alarm shaft 17 is released to rotate, the actuating pin 25 will move against slideable trip pin 26, depressing the latter and thereby depressing arm 37 of bell crank 36. This movement will cause arm 40 to release arm 45 on switch blade 60, and the light circuit will thereby be closed. The ringing of the alarm can be silenced by moving lever 50 on the side of the casing to "silent" position, thus moving an arm 51 into the path of the striker 22. The bulb 14 will still remain lighted and will illuminate the clock dial and the room until the knob 52 on the front of the casing is moved to "off" position. Knob 52 is mounted on a shaft 53 extending through and insulated from the front wall 6 of the casing, and switch blade 60 is mounted on this shaft, as shown at 43. It therefore results that movement of knob 52 to "off" position moves arm 45 of the switch blade back under the bell crank arm 40, opening the light circuit.

The bulb may be lighted when the knob 52 is in "off" position by means of a switch 54, preferably of the rotating snap type, mounted in one side wall of the casing 5. This switch is on a line 55 paralleling line 47, and bulb 14 may thus be illuminated regardless of whether switch blade 60 is in open position.

It will be understood from the above that the operation of switch blade 60 is very rapid.

The shaft 70 of a lever 71 extends through the front wall 6 of the casing 5, and a strip 72 of felt or the like is fixed to the inner end of shaft 70. Movement of lever 71 will rotate shaft 70 to position the felt 72 between the striker 22 and the gong, if it is desirable to have the alarm silenced somewhat.

I claim:

1. The combination with a time switch of a clock train including a shaft, actuating

means rotating with said shaft, trip means in the path of driving movement of said actuating means, said trip means being movable out of the path of reverse movement of said actuating means, and a member normally holding said switch open and adapted to move to release said switch upon movement of said trip means.

2. The combination with a time switch of a clock train including an alarm gong operating shaft, an actuating pin rotating with said shaft, a reciprocable trip pin in the path of driving movement of said actuating pin, said trip pin being movable out of the path of winding movement of said gong operating shaft, a switch element, and a member normally holding said switch open and adapted to move to release said switch upon movement of said trip pin.

EMIL A. MEYER.
